UNITED STATES PATENT OFFICE

WALTER L. WHITING, OF OLYMPIA, WASHINGTON

DESIGN FOR A SWIMMING SUIT

Application filed July 29, 1931. Serial No. 40,709. Term of patent 7 years.

To all whom it may concern:

Be it known that I, WALTER L. WHITING, a citizen of the United States, residing at Olympia, in the county of Thurston and State of Washington, have invented a certain new, original and ornamental Design for Swimming Suits, of which the following is a specification, reference being had to the accompanying drawing, forming part thereof.

I claim:

The ornamental design for a swimming suit, as shown.

WALTER L. WHITING.
